United States Patent Office

Des. 219,059
Patented Oct. 27, 1970

219,059

HANDLE FOR A HOUSEHOLD UTENSIL OR SIMILAR ARTICLE

Monte Levin, New York, N.Y., assignor to Empire
Brushes, Inc., Port Chester, N.Y., a corporation of
New York

Filed Oct. 29, 1969, Ser. No. 19,824

Term of patent 7 years

Int. Cl. D7—99

U.S. Cl. D44—29

FIG. 1

FIG. 2

FIG. 3

FIG. 1 is a top plan view of a handle for a household utensil, embodying my new design;

FIG. 2 is a side elevational view thereof;

FIG. 3 is a bottom plan view thereof; and

FIG. 4 is an enlarged scale cross-sectional view on line 4—4 of FIG. 2.

I claim:

The ornamental design for a handle for a household utensil or similar article, substantially as shown.
